R. L. LONG,
WATER MOTOR FOR EGG BEATERS,
APPLICATION FILED DEC. 24, 1919.

1,337,478.

Patented Apr. 20, 1920.

Inventor

R. L. Long

By Watson E. Coleman
Attorney

UNITED STATES PATENT OFFICE.

RUSSELL L. LONG, OF MORGANTOWN, WEST VIRGINIA.

WATER-MOTOR FOR EGG-BEATERS.

1,337,478.

Specification of Letters Patent. Patented Apr. 20, 1920.

Application filed December 24, 1919. Serial No. 347,092.

To all whom it may concern:

Be it known that I, RUSSELL L. LONG, a citizen of the United States, residing at Morgantown, in the county of Monongalia 5 and State of West Virginia, have invented certain new and useful Improvements in Water-Motors for Egg-Beaters, of which the following is a specification, reference being had to the accompanying drawings.

This invention relates to certain improvements in water motors for beaters and has relation more particularly to a device of this general character especially designed and adapted for use in the beating or whipping 15 of eggs and it is an object of the invention to provide a device of this general character having novel and improved means whereby a dasher or agitating member may be rotated by fluid pressure.

Another object of the invention is to provide a novel and improved device of this general character wherein the motor is adapted to be operated by water discharged from a faucet or the like.

The invention consists in the details of construction and in the combination and arrangement of the several parts of my improved water motor for an egg beater whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a longitudinal sectional view taken through a beater constructed in accordance with an embodiment of my invention and in applied position, a coacting faucet being indicated by dotted lines;

Fig. 2 is a sectional view taken substantially on the line 2—2 of Fig. 1 with a coacting faucet indicated by dotted lines and the flow of the water indicated by arrows; and

Fig. 3 is a fragmentary sectional view illustrating the mounting of the clamping member M.

As disclosed in the accompanying drawings R denotes a receptacle of glass or other desired material and which is provided with a removable cover or lid C. The cover or

lid C is preferably in threaded engagement with an end portion of the receptacle R, although I do not wish to be understood as limiting myself to this particular detail.

H denotes a housing preferably cylindrical in form and having its opposite ends closed. One end portion of the housing H is provided with the equidistantly spaced legs 1, preferably three in number, and which are suitably anchored to the lid or cover C whereby said housing H is carried by the lid or cover C but slightly spaced therefrom. The axial center of the housing H is substantially coincident with the axial center of the receptacle R when the device in its entirety is assembled.

The cover or lid C at substantially its axial center is provided with an opening 2 and the adjacent end of the housing H is provided with an opening 3 in alignment with the opening 2. Disposed through the openings 2 and 3 is an end portion of a rod or shaft S. The rod or shaft S extends within the housing H and is rotatably supported by the opposite ends thereof. The rod or shaft S is also of a length to extend a material distance within the receptacle when the cover or lid C is in applied position.

The portion of the rod or shaft S within the housing H has affixed thereto the equidistantly spaced wings or vanes 6 which operate to rotate the shaft or rod S in a manner now to be described.

The side wall of the housing H is provided with an induction opening 7 defined by an outstanding flange 8 terminating in an inwardly directed flange 9 defining a central opening 10 preferably substantially circular in form.

The wall of the housing H at a point substantially diametrical to the induction opening 7 is provided with an eduction opening 11 substantially defined by a flange 12, affording a discharge nozzle and whereby the fluid such as water emitted from the housing H flows in substantially a solid stream so that splashing or indiscriminate throwing of the liquid as it leaves the housing H is eliminated.

The housing H is engaged with the faucet F in a manner whereby the water discharged from said faucet is delivered within the housing H and for which reason, the spout a of the faucet extends through the opening 10. The force of the water deliv-

ered from the faucet F in conjunction with the wings or vanes 6 causes the rod or shaft S to rotate at a relatively high speed.

When my improved device is in applied position, the longitudinal axis thereof is disposed substantially horizontal and is maintained in working position with respect to the faucet F through the medium of the clamping member M. The clamping member M is carried by a substantially U-shaped yoke 14 secured to the outer end of the housing H and the adjacent portion of the flange 7 at a point slightly to one side of the shaft or rod S.

The clamping member M comprises a shank 15 threaded through an end portion of the yoke 14 and having its inner end portion in swivel connection with a plate 16. The plate 16 is held against turning movement through the medium of a pin 17 extending outwardly therefrom and slidably disposed through an opening 18 produced in the adjacent end portion of the yoke 14.

When the device is in applied position, the yoke 14 straddles the faucet from below and by forcing the plate 16 into firm contact with the faucet, the assembled device is maintained in requisite position to perform its work. By having the yoke 14 positioned as just described, it is assured that the water discharged from the faucet F will strike the blades to one side of the shaft or rod S so that the desired rotation of the rod or shaft S is assured.

From the foregoing description, it is thought to be obvious that a water motor for an egg beater constructed in accordance

with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

1. A water motor for an egg beater and the like comprising a housing provided with induction and eduction openings, a drive shaft extending within the housing, a yoke carried by the housing and adapted to straddle a faucet from below, and a clamping member carried by the yoke for coaction with a faucet.

2. A water motor for an egg beater and the like comprising a housing provided with induction and eduction openings, a drive shaft extending within the housing, a yoke carried by the housing and adapted to straddle a faucet from below, and a clamping member carried by the yoke for coaction with a faucet, the central portion of the yoke being positioned to one side of the drive shaft so that the induction and eduction openings are obliquely related when the housing is applied to the faucet.

In testimony whereof I hereunto affix my signature.

RUSSELL L. LONG.
